VACUUM CLEANER CASING

Gordon W. Florian, Bridgeport, Conn., assignor to Air-Way Electric Appliance Corporation, Toledo, Ohio, a corporation of Delaware

Application February 11, 1954, Serial No. 28,964

Term of patent 7 years

(Cl. D9—2)

FIG. 1

FIG. 2

To all whom it may concern:

Be it known that I, Gordon W. Florian, a citizen of the United States and a resident of Bridgeport, Connecticut, have invented a new, original, and ornamental Design for a Vacuum Cleaner Casing, of which the following is a specification, reference being had to the accompanying drawing, forming a part thereof.

In the drawing:

Figure 1 is a top plan view of a vacuum cleaner casing, showing my new design; and

Figure 2 is a side elevation thereof.

I claim:

The ornamental design for a vacuum cleaner casing, as shown.
